UNITED STATES PATENT OFFICE.

HARRY PICKHARDT, OF NEW YORK, N. Y., ASSIGNOR TO PHOENIX GLASS COMPANY, OF PITTSBURGH, PENNSYLVANIA, A CORPORATION OF WEST VIRGINIA.

DESIGN FOR A LIGHTING-FIXTURE.

46,965.

Specification for Design.

Patented Feb. 16, 1915.

Application filed December 17, 1914. Serial No. 877,825. Term of patent 7 years.

To all whom it may concern:

Be it known that I, HARRY PICKHARDT, a citizen of the United States, residing at New York, in the county of New York and State of New York, have invented a certain, new, original, and ornamental Design for Lighting-Fixtures, of which the following is a specification, reference being had to the accompanying drawing, forming a part thereof.

The figure is a side elevation of a lighting fixture, showing my new design.

I claim:

The ornamental design for a lighting fixture, as shown.

HARRY PICKHARDT.

Witnesses:

E. H. PEED,
A. H. PATTERSON.
